CLAIM

The ornamental design of an element of an audio, video and computer data cartridge, as shown and described.

DESCRIPTION

FIG. 1 is a perspective view from above of element of an audio, video, and computer data cartridge showing our new design;

FIG. 2 is a front elevational view thereof;

FIG. 3 is a top plan view thereof;

FIG. 4 is a right side elevational view thereof;

FIG. 5 is a left side elevational view thereof; and,

FIG. 6 is a bottom plan view thereof.

The broken line showing of cartridge is for illustrative purpose and forms no part of the claim.
